CLAIM

The ornamental design for an octagonal container, as shown and described.

DESCRIPTION

FIG. 1 is a front elevational view of an octagonal container;
FIG. 2 is rear elevational view thereof;
FIG. 3 is a left-side elevational view thereof;
FIG. 4 is a right-side elevational view thereof;
FIG. 5 is a top plan view thereof;
FIG. 6 is a bottom plan view thereof; and,
FIG. 7 is a perspective view thereof.
The broken lines illustrated represent environmental subject matter that forms no part of the claimed design.
